UNITED STATES PATENT OFFICE.

ANDREW W. MITCHELL, OF NORWALK, CONNECTICUT, ASSIGNOR TO R. AN W. HAT SHOP, INC., OF NORWALK, CONNECTICUT, A CORPORATION OF NEW YORK.

ART OF FORMING LINING SURFACES IN HATS.

Application filed July 28, 1920. Serial No. 399,456.

To all whom it may concern:

Be it known that I, ANDREW W. MITCHELL, a citizen of the United States, and a resident of Norwalk, county of Fairfield, and 5 State of Connecticut, have invented an Improvement in the Art of Forming Lining Surfaces in Hats, of which the following is a specification.

This invention relates to the treatment of 10 the inner surfaces of hats. One of the objects thereof is to provide a practical and effective art whereby the inner surfaces of hats are given an improved appearance. Another object is to provide an art of the 15 above nature adapted to so affect the appearance of the interior of the hat that a lining member is rendered superfluous. Other objects are to provide an art of the above nature which may be simply and quickly 20 carried on and by which the character of the hat as a whole is improved.

Other objects will be in part obvious and in part pointed out hereinafter.

The invention accordingly consists in the 25 several steps and relation of certain of the same with respect to one or more of the others thereof, all as will be illustratively herein described and the scope of the application of which will be indicated in the 30 following claims.

In the accompanying drawing in which are illustratively shown the conditions of the hat during various steps of the process,

Figure 1 shows the hat in normal position in readiness for treatment, a portion of the crown being broken away to show the inner surface thereof;

Figure 2 shows a hat turned inside out, the inner surface of the crown having been 40 treated, a portion of the crown being broken away to show the exterior surface of the crown; and

Figure 3 shows a hat in normal position after the completion of the process, a portion of the crown being broken away to 45 show the interior surface.

Similar reference characters refer to similar parts throughout the several views of the drawing.

50 My improved art is especially applicable to the manufacture of the so-called "soft hats" as distinguished from stiff hats, and to hats made of felt as distinguished from hats made of other material, and its advantages are chiefly attained when applied

to these soft felt hats although certain of its features may be used on hats of other type.

Assuming that a hat of the above nature has been brought to size, shape and condition by any approved method and has been dyed to the desired color, it is first inverted, or turned inside out. It may here be noted that the term "invert" is used herein to denote an action by which the article acted upon is turned inside out, and that the term "revert" is used to denote a contrary action or a restoration to the normal condition of the article.

With the hat in this condition, the inner 70 surface of the crown or body of the hat is scratched with a wire brush to roughen or loosen it, and liquid color or dye is applied to this surface, preferably by a sponge or brush. This coloring is preferably applied down to a line which will be covered by the leather band of the hat and yet will not quite reach the brim of the hat with a chance of accidentally extending on to the brim. However, many advantages of 75 the invention may be achieved even if the color is applied to the entire inner surface of the crown or body of the hat. This color or dye is distinctive with respect to the color of the hat as a whole, and is preferably of 80 a brighter shade or otherwise adapted to correspond with the silk linings now widely used in hats. It may be noted at this point 85 that the term "distinctive" is used in a broad sense to denote a characteristic of the color by which it differs from the color of the hat as a whole. The hat is then steamed and dried, and the inner surface of the crown colored as above is buffed with a felt wheel, the hat in its inverted condition being fitted on a block for this operation.

After the inner surface has been buffed to a bright finish, the crown of the hat is reverted into its normal condition and the outer surface is pounced or finished.

The hat is then again inverted and again buffed on its inner colored surface and slicked with hot lure.

The hat is thereupon again reverted and its outer surface and brim slicked, whereupon it is pressed with a hydraulic press. The final step is preferably a last slicking with hot lure of the inner surface of the crown just before packing.

A clearer understanding of certain of the 110

steps of my process as above described may be realized by reference to the accompanying drawings. Fig. 1 shows a hat after it has been brought to size, shape and condition as desired, the interior surface 10 and exterior surface 11 of the crown as well as both surfaces of the brim 12 having been dyed to the desired exterior color of the hat. In Fig. 2 the hat has been inverted or turned inside out and a desired distinctive color has been applied to the normal interior surface 10 of the crown, the color being applied down to a line, as 13, which will be covered by the sweat band of the hat thus obviating the danger of the color accidentally extending onto the brim 12. Fig. 3 shows the hat reverted to normal position after completion of the process, the interior surface 10 of the crown having been given a distinctive color relative to that of the outer surface 11 of the crown and of the brim 12.

The above I have found to produce excellent results but it is to be understood that all of the above steps are by no means vital and that dominant advantages of my invention may be gained if one or more of them be omitted.

By the above process the hat is given an inner surface of extremely attractive appearance and is much lighter and cooler than if the usual lining member were employed. The name or label may be applied directly on the surface of the hat instead of to a lining, and the cost of the hat is substantially reduced.

As various changes might be made in the above process without departing from the scope of this invention, it is to be understood that all matter herein described is to be interpreted as illustrative and not in a limiting sense.

I claim as my invention:

1. An art of the nature of that herein described which consists in inverting a hat formed of a single thickness of material, applying a distinctive color to the inner surface of the crown directly to said material, and reverting the hat.

2. An art of the nature of that herein described which consists in inverting a hat, roughening the inner surface of the crown thereof, applying a distinctive color to such surface, and reverting the hat.

3. An art of the nature of that herein described which consists in applying a distinctive color to the inner surface of the crown of a hat and thereafter buffing such surface with a felt wheel.

4. An art of the nature of that herein described which consists in roughening the inner surface of the crown of a hat, applying a distinctive color to said surface, steaming and drying said surface, and thereupon buffing said surface.

5. An art of the nature of that herein de-

scribed which consists in applying a distinctive color to the inner surface of the crown of a hat, finishing the outer surface thereof, inverting the hat, and buffing its inner surface.

70

6. An art of the nature of that herein described which consists in applying a distinctive color to the inner surface of the crown of a hat, inverting the hat, buffing its inner surface, slicking its inner surface with hot lure, reverting the hat, slicking its outer surface, and pressing the hat.

7. An art of the nature of that herein described which consists in applying a distinctive color to the inner surface of the crown of a hat, buffing it in inverted form, reverting and finishing the hat, and again inverting and buffing it.

8. An art of the nature of that herein described which consists in applying a distinctive color to the inner surface of the crown of a hat, buffing it in inverted form, reverting and finishing the hat, again inverting and buffing it, again reverting the hat, slicking its outer surface, and pressing it.

85

9. An art of the nature of that herein described which consists in roughening the inner surface of the crown of a hat, applying a distinctive color thereto, and buffing it in inverted form.

90

10. An art of the nature of that herein described which consists in applying a distinctive color in liquid form to the inner surface of the crown of a hat, steaming the hat, drying it, and buffing its inner surface in inverted form.

100

11. An art of the nature of that herein described which consists in applying a distinctive color to the inner surface of the crown of a hat and buffing such surface with the hat in inverted form, reverting the hat, finishing its outer surface, again inverting the hat and buffing its inner surface, slicking its inner surface with hot lure, again reverting the hat, slicking its outer surface, pressing it, and again slicking its inner surface.

110

12. An art of the nature of that herein described which consists in inverting a hat, roughening the inner surface of the crown of the hat, applying a distinctive color in liquid form to the inner surface of the crown, steaming the hat, drying the hat, buffing the inner surface of the crown, reverting the hat, finishing its outer surface, again inverting the hat and buffing its inner surface, slicking its inner surface with hot lure, again reverting the hat, slicking its outer surface, pressing the hat, and again slicking its inner surface with hot lure.

115

In testimony whereof, I have signed my name to this specification this 22nd day of July, 1920.

ANDREW W. MITCHELL.
